MATTHEW MULLINEUX, OF VANCOUVER, BRITISH COLUMBIA, CANADA.

FILLING AND VENTING APERTURE FOR GASOLENE-TANKS.

1,031,283.

Specification of Letters Patent.

Patented July 2, 1912.

Application filed March 25, 1911. Serial No. 616,984.

To all whom it may concern:

Be it known that I, MATTHEW MULLINEUX, citizen of the Dominion of Canada, residing at Vancouver, in the Province of British Columbia, Canada, have invented a new and useful Filling and Venting Aperture for Gasolene-Tanks, of which the following is a specification.

This invention relates to a filling and 10 venting aperture for a gasolene tank which is closable by a cover hinged to the deck plate of the aperture and susceptible of being locked thereto, and my object has been to provide under one cover a closable filling 15 and venting aperture of this kind having an ample provision for the escape from the tank of the air of displacement in a manner that is clear from interference from the inflowing gasolene.

20 Owing to the extreme lightness of gasolene where a tank filling aperture is dependent for the escape of the displaced air on the chance accommodation through the same aperture, much gasolene is wasted by blow-backs, and the same trouble occurs even when a separate venting tube is furnished, if an insufficient area is provided or if the filling pipe terminates in proximity to the entrance to the vent pipe. These objections 25 30 I have overcome in the invention which is the subject of this application by providing a filling and venting aperture which are concentric with one another and closable by the same plug or cap, the inner or filling tube 35 projecting some little distance into the tank and the venting space outside of the filling tube and connected to the top of the tank.

The invention is particularly described in the following specification, reference being 40 made to the drawings by which it is accompanied, in which:

Figure 1 is a vertical section on the line A—A of Fig. 2 showing the application of the device to a tank, and Fig. 2, is a sectional plan of the same taken on the line B—B of Fig. 1.

In these drawings 2 represents the deck line of a launch 3 being the top of a gasolene tank therebeneath. Soldered in the top 50 of the tank but not projecting within it is a pipe 4 the upper end of which is threaded to receive the boss 5 of the apertured deck plate 6. This deck plate 6 is provided with a cover 7 hinged at 8 and jointing upon a 55 shouldered seat 9 outside of the diameter of the pipe 4 on which seat 9, which should

be furnished with an insertion joint, the hinged cover 7 seals the opening from the tank. The cover 7 is provided with a lock 10 by which it may be secured in the closed position. On the hinge pin 8 of the cover is a spring 11 tending to throw the cover open when the same is released by the withdrawal of the lock bolt from the hasp 12 of the cover.

Concentrically supported in any convenient manner within the tube 4 is an inner tube 14 so as to leave an annular space 15 between it and the outer tube 4 and this inner tube, which is the filling tube, projects 60 below the top of the tank 3 a sufficient distance to insure that the gasolene poured through it in filling will not be caught by the current of the air of displacement flowing out through the annular space 15 from 65 the upper part of the tank.

The inner tube 14 is here shown as having a threaded upper end to engage a corresponding screw thread nut in three or more radial projections 16 from the inner side of 70 the aperture in the deck plate 6. This forms a simple and convenient manner of supporting the filling pipe 14 within the outer pipe 4 so as to leave a venting passage 15 between the two pipes. The manner of supporting 75 the inner pipe within the outer is comparatively secondary. The essential feature is the provision of one within the other and closable with a sealing or locking cover.

I therefore claim as my invention:

1. In a filling device for tanks, a deck plate having an aperture therein, a hinged cover seating around the aperture to close the same, a tank, a tube connecting the aperture in the deck plate with the tank, a second 95 tube maintained approximately concentric within the aperture and extending downward within the beforementioned tube into the tank, and means for supporting the inner tube from the deck plate said means 100 comprising radial projections from the inside of the deck plate and means for securing the tube to these projections.

2. In a filling device for tanks, a deck plate having an aperture, a tube connecting 105 said aperture to the tank, a hinged and locked cover seating around and closing this aperture, a second tube approximately concentric within the aperture but projecting within the tank to a level below the connection of the larger tube, said inner tube having a threaded end and radial projections 110

from the deck plate threaded to receive the threaded end of said inner tube.

3. A device of the class described comprising a deck plate having a depending tubular portion internally threaded at the lower end and provided with a plurality of inwardly projecting internally threaded lugs near its upper end, a tank, a pipe threaded into said lower end of said tubular portion and connected with said tank at the top, and a second pipe whose upper end is threaded into said lugs and whose lower end projects into said tank and terminates below the end of said first mentioned tank, and a cover plate carried by said deck plate to close the entrance to said tubular portion.

4. A device of the class described comprising a deck plate having a downwardly projecting tubular portion and a depression in its upper face registering with said tubular

portion, said tubular portion including inwardly projecting lugs adjacent to said depression, a pipe held by said lugs at its upper end and projecting downwardly through said tubular portion, a second pipe secured in said tubular portion and surrounding said first mentioned pipe, said second pipe terminating short of the end of said first mentioned pipe, and a tank with which said pipes communicate, together with a cover plate for closing said depression and thereby closing said pipes. 25 30

In testimony whereof I have signed my name to this specification in the presence of the two undersigned witnesses.

MATTHEW MULLINEUX.
